US0D1040125S

(12) **United States Design Patent** (10) Patent No.: **US D1,040,125 S**
(45) Date of Patent: **** Aug. 27, 2024**

(54) **TELEVISION RECEIVER**

(71) Applicant: **LG Display Co., Ltd.**, Seoul (KR)

(72) Inventors: **Sunghyun Heo**, Paju-si (KR); **Jaehan Kim**, Paju-si (KR); **Sangyoon Byun**, Paju-si (KR); **Lisie Park**, Paju-si (KR); **Hongseok Seo**, Paju-si (KR); **Minkwan Seo**, Paju-si (KR)

(73) Assignee: **LG DISPLAY CO., LTD.**, Seoul (KR)

(**) Term: **15 Years**

(21) Appl. No.: **35/516,585**

(22) Filed: **May 6, 2022**

(80) **Hague Agreement Data**

Int. Filing Date: **May 6, 2022**

Int. Reg. No.: **DM/222748**

Int. Reg. Date: **May 6, 2022**

Int. Reg. Pub. Date: **Mar. 10, 2023**

(30) **Foreign Application Priority Data**

Nov. 11, 2021 (KR) 30-2021-0053668

(51) LOC (14) Cl. **14-03**

(52) U.S. Cl.

USPC **D14/126**
